(57) **CLAIM**

The ornamental design for a lighting fixture, as shown and described.

DESCRIPTION

FIG. 1 is a perspective view of a lighting fixture according to an example embodiment of the design;

FIG. 2 is a top view of a lighting fixture according to an example embodiment of the design;

FIG. 3 is a bottom view of a lighting fixture according to an example embodiment of the design;

FIG. 4 is a front view of a lighting fixture according to an example embodiment of the design;

FIG. 5 is a back view of a lighting fixture according to an example embodiment of the design;

FIG. 6 is a side view of a lighting fixture according to an example embodiment of the design;

FIG. 7 is another side view of a lighting fixture according to an example embodiment of the design;

FIG. 8 is a perspective view of a lighting fixture according to an example embodiment of the design;

FIG. 9 is a top view of a lighting fixture according to an example embodiment of the design;

FIG. 10 is a bottom view of a lighting fixture according to an example embodiment of the design;

FIG. 11 is a front view of a lighting fixture according to an example embodiment of the design;

FIG. 12 is a back view of a lighting fixture according to an example embodiment of the design;

FIG. 13 is a side view of a lighting fixture according to an example embodiment of the design; and,

FIG. 14 is another side view of a lighting fixture according to an example embodiment of the design.

The broken lines with the various embodiments of the claimed design and the spaces therein are included for illustrating environmental aspects only and form no part of the claimed design.

1 Claim, 14 Drawing Sheets
